CONTINUOUS INDUCTIVE TRAIN CONTROL SYSTEM

Filed Aug. 5, 1925

C. F. Estwick, ^{inventor}

By Neil H. Weston,
his attorney

UNITED STATES PATENT OFFICE.

CHARLES F. ESTWICK, OF ROCHESTER, NEW YORK, ASSIGNOR TO GENERAL RAILWAY SIGNAL COMPANY, OF ROCHESTER, NEW YORK.

CONTINUOUS INDUCTIVE TRAIN-CONTROL SYSTEM.

Application filed August 5, 1925. Serial No. 48,313.

This invention relates to train control and more particularly concerns an automatic train control system of the continuous inductive three-position type.

- 5 In the three-position type of automatic train control system, influences corresponding to traffic conditions are transmitted to a moving vehicle by means of two alternating currents flowing in the track rails. One of these 10 currents, usually termed the track phase current, flows in the two track rails in series, while the other current termed the line phase or simplex current flows in the two track rails in multiple. The control influences are 15 usually transmitted by cutting off the track phase current in an occupied or danger block and by reversing the instantaneous polarity of the line phase current in the first block in the rear of an occupied block.
- 20 In train control installations in congested districts, large variations in the line phase control currents sometimes occur as a result of stray currents produced in the track rails by differences in ground potentials at various 25 points in a block, these ground potentials being caused by alternating current power lines, by signaling or train control circuits on adjacent trackways, or by other sources of electrical energy. In order to obtain reliable 30 operation of the car-carried control apparatus, it is desirable to have at least one of the control currents of a constant value, and these large variations in the line phase current caused by stray potentials are therefore very undesirable.

- With the above and other considerations in mind it is proposed in accordance with the present invention to provide a system of automatic train control of the continuous inductive type in which car-carried means are provided for supplying a constant current to the control apparatus, which current corresponds to the frequency and flow of the line phase control current but which does not vary in amplitude in accordance with variations in the line phase current.

Other objects, advantages and characteristic features of the invention will be apparent as the description thereof progresses.

- 50 In describing the invention in detail, reference will be made to the accompanying drawing, in which a single figure has been shown, representing the car-carried and trackway apparatus of a train control sys-

tem embodying the present invention in a simplified and diagrammatic manner.

The present invention is adapted for use with many different forms of continuous inductive control systems, but the system chosen to illustrate the nature of the invention is of the well known three-position type. As this type of train control system is well known to those skilled in the art, its construction and operation will be very briefly described.

Referring to the trackway apparatus, the track rails 1 have been shown divided into blocks by the insulating joints 2, the block I and the ends of the two adjacent blocks H and J having been shown. As the apparatus and circuits used in connection with the various blocks are substantially identical, corresponding elements will be referred to by like reference characters having distinctive exponents.

An alternating track circuit current, which is also the track phase train control current is impressed upon the two track rails in series at the entrance end of each block by means of the transformer 3 and a circuit which is obvious from the drawings, the usual track resistance 4 being included in this circuit. An alternating current track relay 5, normally energized by the track circuit current, is connected across the track rails at the entrance end of the block, its local phase being energized by a suitable local source of alternating current (not shown). When a train or vehicle is located in the block its wheels and axles shunt the track circuit and track phase train control current from the track rails and cause the track relay 5 at the entrance end of the block to be de-energized. Line phase or simplex train control current is supplied to the two track rails of the blocks in multiple from the transformer 6, the circuit for this current under clear traffic conditions being traceable as follows:—from the transformer 6, wire 7, contact finger 8¹ and front contact of the track relay 5¹, wire 9, balance resistance 10, two track rails of the block I in multiple, balance resistance 11, wires 12 and 13, front contact and contact finger 14¹ of the track relay 5¹ and wire 15 to the transformer 6. It is obvious that when a train is located in a given block, say the block J, the track relay 5¹ at the entrance end of this block is de-energized, retracting its contact fingers 8¹ and 14¹. This causes a reversal of the instantaneous

polarity of the line phase current supplied to the block I, the path of this reversed line phase current being obvious from the drawings.

5 Wayside signals of the semaphore, color light or other suitable type may or may not be used in connection with the system of the present invention, but for the purpose of illustration, semaphore wayside signals Z 10 have been shown at the entrance end of each block, their well known operating circuits and devices being omitted for the sake of simplifying the drawing.

Referring now to the car-carried apparatus, a railway vehicle has been conventionally represented in the block H by the wheels and axles 16, the normal direction of traffic being indicated by the arrow. This vehicle is provided with two sets of inductive receiving coils, the track phase receiving coils 17 being mounted in front of the leading axle of the vehicle in inductive relation to the track rails, and the line phase receiving coils 18 being mounted to the rear of at least one of the 20 vehicle axles, and preferably to the rear of the locomotive or other equipped vehicle, and in inductive relation to the track rails. The track phase receiving coils 17 are connected through a suitable amplifying device AT, 25 preferably of the audion tube type, to one of the windings 19 of a polyphase main relay MR through circuits which are obvious from the drawings. The line phase receiving coils 18 are connected through an amplifier 30 AL to a polarized relay P, the output circuit of this relay being connected through a transformer 20 to the other winding 21 of the relay MR. The output circuits of the amplifiers AT and AL are provided with suitable tuning 35 condensers CT and CL respectively by means of which the necessary phase relation between the currents in these circuits may be obtained, although the inductances 4, 4° can be used to obtain this necessary phase relation 40 between currents before reaching the car.

The polarized relay P comprises a permanent magnet or field piece 22 having a polarized armature 23 suspended between the pole pieces thereof from the support 24 as shown. 45 A winding 25 is provided on the polar armature 23, being connected to the output circuit of the line phase amplifier AL through a circuit which is obvious from the drawings. The armature 23 is provided with two flexible contacts 26 and 27 which are adapted to contact with suitable stationary contacts 28 and 29 respectively when the armature 23 is swung to one or the other of its extreme positions. The stationary contacts 28 and 29 are 50 connected by the wires 30 and 31 respectively to the positive and negative terminals of the battery 32, the midpoint of this battery being connected by a wire 33 to one terminal of the primary winding of the transformer 20. 55 The armature 23 of the polarized relay P is

connected by a wire 34 to the other terminal of the primary winding of the transformer 20.

The main relay MR has two movable contact fingers 35 and 36 which operate to control the energization of circuits for the car-carried control apparatus. As the particular form of control used forms no part of the present invention, and as this control may be obtained in a variety of ways by the use of any of a number of suitable devices well known in the art, an extremely simple form of control apparatus has been shown. The control apparatus has been shown as consisting of a medium speed brake applying device MB and a low speed brake applying device LB, it being assumed that when the device MB is de-energized the vehicle brakes will be applied until the train has been brought to a suitable medium speed such as forty miles per hour, and that when the device LB is de-energized the vehicle brakes will be applied until the vehicle speed has been reduced to a suitable low value, such as fifteen miles per hour.

50 Cab signals of any suitable type may or may not be used in connection with the present invention and in the embodiment shown the cab signals G, Y and R, representing clear, caution and danger traffic conditions respectively, have been shown, it being assumed that these signals comprise lights, discs or other suitable indicating devices which are displayed when energized.

55 *Operation.*—All of the apparatus and devices shown in the drawing have been shown in their normal operated condition, that is, with the train proceeding under clear traffic conditions ahead and with all circuits properly energized. For the purpose of simplifying the wiring diagrams, the letters B and C 100 have been used to denote the positive and negative terminals of a suitable car-carried source of energy, such as a storage battery.

105 Considering first the operation of a train under clear traffic conditions ahead, assume that the train 16 is proceeding in the block H, there being no other train in either of the blocks I or J. Under these conditions track and line phase train control currents flow in the track rails of the block H and induce voltages in the receiving coils 17 and 18 respectively. The voltages induced in the track phase receiving coil 17 are amplified by the track phase amplifier AT and impressed upon the winding 19 of the main relay MR. The 110 voltages induced by the line phase control currents are amplified by the line phase amplifier AL and impressed upon the polarizing winding 25 of the polarized relay P. It is assumed that the output circuit of the amplifier AL is arranged to produce an alternating current, and the flow of this alternating current through the polarizing coil 25 on the 115 polar armature 23 of the relay P causes this armature 23 to vibrate or oscillate between the 120

5 pole pieces of the permanent magnet 22 according to the usual operation of the polarized relays. The vibration of the armature 23 causes current from the battery 32 to be im-
 10 pressed upon the primary winding of the transformer 20, the polarity of this current be-
 ing reversed in synchronism with the oscil-
 lations of the armature 23. An alternating
 current is produced upon the winding 21 of
 15 the main relay MR through a circuit which
 is obvious from the drawings. The ener-
 gization of the windings 19 and 21 of the
 main relay MR cause this relay to assume its
 20 normal position as shown, energizing the
 medium speed brake applying device MB and
 the clear cab signal G through circuits which
 are obvious from the drawings. The low
 25 speed brake applying device LB is energized
 through the contact finger 36 of the main re-
 lay and an obvious circuit. With the clear
 cab signal G energized, the engineer is ap-
 prised of the fact that he is proceeding in
 30 clear territory, and since the brake applying
 devices MB and LB are energized, he may
 35 proceed without automatic restriction so long
 as clear traffic conditions exist.

Considering now the operation of the apparatus under caution traffic conditions, assume that a train or vehicle is located in the 30 block J and that the train under consider-
 ation enters the block I in which caution traffic conditions exist. The line phase train control current flowing in the track rails of the block I are of reverse instantaneous polarity as compared with line phase control current flowing in a clear block for reasons hereinbefore described. This line phase current of reverse instantaneous polarity operates the polarized relay P in the manner de-
 40 scribed in connection with operation in a clear block, and produces an alternating current in the winding 21 of the main relay MR which is reversed in instantaneous polarity with respect to the current flowing in this winding 45 when proceeding in a clear block. The winding 19 of the main relay MR is energized from the track phase receiving coils 17 in the usual manner and the main relay, being supplied with current of normal polarity in one of its 50 windings and of reverse polarity in the other of its windings, operates to swing its contact fingers to their reverse position, as represented by the diagonal dotted lines. The energizing circuit for the medium speed brake applying device MB and for the clear cab signal G is broken, and these devices are de-energized, causing a brake application which persists until the vehicle speed has been reduced to the assumed medium value of 40 miles per 55 hour. The caution cab signal Y is energized through the contact finger 35 of the main relay MR and a circuit which is obvious from the drawings. The low speed brake applying device LB is energized through the contact 60 finger 36 of the main relay in its reverse posi-

tion, and a circuit which is obvious from the drawing. After the train speed has been reduced to the medium value the vehicle may proceed without further restriction through-
 65 out the caution block.

As the vehicle passes out of the block I and enters the block J in which a train is located, the main relay MR is de-energized due to the fact that no track phase current flows in the track rails of the block J when a train 70 is standing in this block. Line phase current of normal polarity however flows in the track rails J in multiple and causes the energization of the winding 21 of the main relay MR in the manner described in connection with train 75 operation in a clear block. The de-energization of the main relay MR causes its contact fingers 35 and 36 to assume their de-energized positions as represented by the vertical dotted lines, thus causing the de-energization of the low speed brake applying device LB and the cab signal Y, and causing the energization of the danger cab signal R, the circuits being obvious from the drawing. De-energization of the low speed brake applying device LB initiates an automatic brake application which persists until the vehicle speed is reduced to a suitable low value, after which the train may proceed at this low speed without further restriction through the danger 85 block.

It is seen that the alternating current supplied to the winding 21 of the main relay MR is of a constant value in spite of variations in the line phase current flowing in the track 100 rails, the current in the winding 21 being dependent only on the voltage of the battery 32 which can readily be maintained substantially constant. The alternations of the line phase current are faithfully reproduced by the polarized relay P in the energizing circuit for the winding 21, so that the influences transmitted from the rackway by the reversal of the instantaneous polarity of the line phase current reliably indicates traffic conditions 105 ahead.

As the present invention has been described in connection with a rather specific train control system including certain specific devices, it should be clearly understood that the invention is not limited to the use of the particular means shown and described, and that various changes, adaptations and modifications may be made without departing from the scope of the invention as defined by the 115 appended claims. For example, the polarized relay P might be replaced by any other suitable means for properly synchronizing the variations of current in the coil 21 of the main relay MR in accordance with the alterna- 120 tions received by the line phase receiving coils 18.

What it is desired to secure by Letters Patent is:—

1. In an automatic train control system, in 130

combination with an alternating control current of substantially constant magnitude and an alternating control current of varying magnitude flowing in the track rails, car-carried apparatus including a polyphase alternating current relay, means for supplying an alternating current corresponding in frequency to said trackway control current of substantially constant magnitude to one phase of said relay, and means for supplying a substantially constant current of a frequency corresponding to said control current of varying magnitude, the last said means including contacts operated by an armature for alternately completing circuits of opposite polarity from direct current sources of constant potential to the other phase of said relay.

2. In an automatic train control system, means for transmitting influences corresponding to traffic conditions from the trackway to a moving vehicle comprising, an alternating control current of varying magnitude flowing in the track rails, car-carried apparatus including inductive means arranged to have voltages induced therein corresponding to said trackway control current, a polarized relay having an armature magnetized by said induced voltages, an electro-responsive device, and contacts operated by said armature

to alternately close circuits of opposite polarity including constant sources of voltage and said electro-responsive device, whereby said electro-responsive device is supplied with an alternating current of constant magnitude and of a frequency corresponding to said trackway control current.

3. In an automatic train control system of the continuous inductive type, the combination with a trackway having two distinctive alternating currents flowing in the rails thereof, a two-element alternating current relay on a railway vehicle movable over said trackway, inductive influence receiving means on the vehicle for energizing one element of said relay in accordance with one of said trackway currents, a tuned reed relay vibrated in accordance with the alternations of the other of said trackway currents, and means for applying current to the other element of said two-element relay in accordance with the vibration of said tuned reed relay, whereby variation of magnitude of said other trackway current when above a certain value does not vary the degree of energization of said two-element relay.

In testimony whereof I affix my signature.

CHARLES F. ESTWICK.
